ADJUSTABLE CLOSING DEVICE FOR A BURIAL CASKET

Carrel D. Cole, Houston, Tex., assignor of fifty percent to Carl E. Creasy and fifty percent to Elwood E. Creasy, both of Bluefield, Va.

Application April 5, 1955, Serial No. 499,370

4 Claims. (Cl. 292—247)

This invention relates to burial casket hardware and more particularly to closing and latching devices associated with the top closure panels and the top molds of the caskets. The devices may also embody lock mechanisms whereby these units of caskets may be locked together.

Since the last closing of a burial casket is in most instances performed in the presence of a group of people that include members of the immediate family of the deceased, and since the final closing of a burial casket is usually a part of the burial ceremony, it should be accomplished easily and positively, and in a dignified manner.

With the usual devices now being used, that is, standard panel catches, screws, bolts, etc., it is frequently impossible for the funeral director, or assistant, to properly close a casket at the funeral service without pulling and tugging at the casket top thus causing embarrassing delays and commotion. This difficulty in closing a burial casket is usually due to the fact that the catches and hinges are fixed to the casket parts before any lining or upholstering is done. The casket may close perfectly at this stage of manufacture, but, after the lining and decorative upholstering is added, it is often found that the procedures used in lining the casket has sprung the hinges or panel, or the bulk of the upholstering itself may cause difficulty in closing. The standard panel catches do not perform any function of assisting in aligning the panel and the top segments to bring about proper closure.

One of the principal objects of this invention is to provide devices, each comprising two units, one of which is attached to the top closure panel and the other to the top mold, so constructed and arranged that, upon manipulation of the device, the top closure panel will, if out of proper alignment with the mold, be drawn into proper and slightly relationship with the mold, or if the casket lining and decorative upholstering is so bulky as to have sprung the hinges or render closing of the panel otherwise difficult, the manipulation of the device will enable the attendant to properly close the casket with ease, instead of the awkward procedure of pulling and tugging or exerting pressure upon the panel by bearing upon it.

Another important object is to provide devices of the character described, parts of which can be temporarily mounted on the top panels of the caskets in the approximate position desired for use, at the factory, or prior to placing of linings and upholstering, and then more securely fixed to the panels after the bed, body skirt, cushioning, smocking, etc., have been placed, and tests made to determine the best location of the parts of the devices so as to assure easy and slightly closing.

Another object is to provide devices of the character described which are susceptible of embellishment or treatment to render them decorative and to harmonize in design with other decorations in or on the caskets.

A further object is to provide a device of this character, the major parts of which are carried by the casket

2

top panels, and so constructed and arranged that they are out of sight to viewers, when the casket is open, that is, with the top panel raised to open upright position. The standard catches now in use are mounted in the center of the top edge of the panel by drilling or cutting through and since the standard type catch extends down into the top mold it, by necessity is visible when the casket is open and the panel is raised to a perpendicular position. This tends to distract attention away from the beauty of the art work of the interior decoration and is most objectionable. Using a device according to the present invention, the panel, as viewed when open, remains an unbroken frame for the decorations built into it.

15 Other objects and advantages will appear in the following detailed description of one embodiment of the present invention, taken in connection with the accompanying drawings, forming a part of this specification, and in which drawings:

20 Fig. 1 is a perspective view looking toward the front of a burial casket equipped with an adjustable closing device according to the present invention, the top panel being in an open position.

Fig. 2 is a similar view, but with the top panel in a 25 closed and latched or locked position.

Fig. 3 is a detail view in plan of the adjustable closing device, and showing the manner in which parts may be shaped to have pleasing appearance.

Fig. 4 is an enlarged sectional view on the line 4—4 30 of Fig. 2, showing the device as applied to the top mold and panel of the casket and omitting any interior trim and decorations.

Fig. 5 is an enlarged fragmentary sectional view on the line 5—5 of Fig. 1 also omitting any of the interior trim 35 and decorations.

Fig. 6 is a sectional view on the line 6—6 of Fig. 4.

Fig. 7 is a plan view of a metal stamping constituting a typical adjustable hinge plate which forms a part of the device.

Fig. 8 is a detail view of the working parts of a typical lock mechanism which may be incorporated as a part of the device, the view being on substantially the line 8—8 40 of Fig. 4.

Fig. 9 is an enlarged plan view of a typical head of 45 an element of the device, adapted to be secured to the casket mold.

In the drawings is shown a typical burial casket 10 comprising an elongated body portion or shell 11, including a top mold 12, and an elongated top closure panel 14 hingedly carried by the rear portion of the top mold in the usual or any approved manner. In Fig. 1, suitable upholstering 15, and decorative trim 16 thereabout are shown, carried by the inner side of the panel 14, and within the body portion 11, suitable upholstering 13 and pillow 17 are illustrated. The panel 14 may be held in an upwardly extending position for viewing the interior of the body portion 11 by any suitable device, such as the cord 18 having its end portions secured to the body 11 and panel 14.

60 The closing device comprises a dog 20, which may be rather inconspicuous in that it includes only a head 21 extending outwardly from the face 22 of the top mold at the front portion of the casket, to which it is secured; a lever 24 with means 25 secured to the top front portion of the top closure panel 14, pivotally mounting the lever 24 to swing about an axis parallel to the longitudinal axis of the panel 14; and a link 26 pivotally carried at one end portion by the lever 24 to swing about an axis parallel with the pivotal axis of lever 24 and provided 65 at its other end portion with a downwardly and rearwardly opening pocket 27 for releasably engaging and

concealing the dog 20, when the lever 24 is in juxtaposed relation to the closed top panel 14, as shown in Fig. 2 and is obvious from an inspection of Figs. 4-6.

More specifically it is preferred to provide a machine screw 28 for use with sheet metal top molds 12, the shank 29 of the screw having a Phillips flat head 21, and a nut 30 on the shank to constitute the dog 20 as shown in Figs. 4 and 9; to make the lever 24 a hollow metal stamping or casting comprising an enlarged or major body portion 31 and a reduced or minor portion 32 which provides shoulders 33 adjacent each side of portion 32 for a purpose to be subsequently set forth, the hollow lever having a cavity 34 open to its underside; to have the means 25 comprise a hinge plate 35 fabricated to provide a main body portion 36 and spaced ears 37, each provided with a perforation 38 as shown in Fig. 7, which, when the ears are bent in right angular relation to plane of the body portion 36 as shown in Figs. 3-6, hold a pivot pin 40 passing through perforations 41 in the reduced or minor portion 32 of lever 24 and extending across the cavity 34 thereof; and, to mold or fabricate the link 26 so as to be of U-shape, with a bight portion 42 in which the pocket 27 is formed, and arms 43 having pivoted connection with the lever 24 as by a cross pivot pin 44 secured to the end portions of the arms opposite to the bight portion 41 and extending through openings 45 in lever 24.

Thus, it will be noted that the Phillips head 21 of screw 28 is very inconspicuous, when the casket is open, as shown in Fig. 1 and may be regarded by onlookers more as an ornament than a mechanical device. The hollow lever 24 may be pressed or molded to an ornamental shape, so as to have more the appearance of an ornamental medallion than a mechanical device and the metal plate 35 may be concealed in the cavity 34 of the lever, except when the lever is moved from its position in juxtaposed relation to the panel top. The U-shaped link 26 has more the appearance of a loop shaped handle than a mechanical contrivance.

In order that the hinge plate 35 and the lever 24, with pivot pins 40 and 44, may serve as typical means for tensioning the link 26, when the panel 14 is in a closed position and the dog 20 is engaged in and concealed by the pocket 27, so as to draw an out-of-line top panel back into place and thus avoid the necessity of an attendant grasping it or pulling or tugging as previously described, or to compress decorative material in the casket which might otherwise require an attendant to press upon the top panel in order to close it, the following are preferred characteristics of the device:

The pivot pin 44 is located in an over center position so that its axis is to one side of the axis of pivot pin 40 when the lever 24 is in a normal position in juxtaposed relation to the top panel 14 and the link 26 firmly engages the dog 20 as shown in Fig. 4, the "over center" position being clear from a consideration of the double dot and dash line x—x passing through the zone of contact of the link 26 with the dog 20 and through the axis of pivot pin 44, but below the axis of pivot pin 40. Also the downwardly and rearwardly opening pocket 27, as shown in Figs. 3, 4 and 6 is preferably of V-shape with the opposite walls 47 diverging outwardly from an apex zone 48, to the inner side 49 of the bight portion 42, and with the opposite walls 47 incut as indicated at 50 to have anchoring relation with the tapered head 21. Thus, if the top panel 14 is out of line with the top mold 12, it may be drawn into line by manipulation of the lever 24 and the guiding action of either wall 47—whatever may initially engage the dog 20—until the dog is located in the apex zone 48 of pocket 27.

Since, in the example shown, the ears 37 extend between the lever portion 32 and the arms 43, filler pieces 52 in the nature of washers may be interposed one at

each side of portion 32 and the adjacent arm 43, these filler pieces each being substantially of the same thickness as the thickness of the adjacent ear 37.

In order to render the device adjustable to meet various conditions encountered after the casket shell has been upholstered, etc., the main body portion 36 of plate 35 is preferably provided with an elongated slot 53, the longitudinal axis of which is normal to the axis of the pivot pin 40, the slot 53 cooperating with a head 54 of a screw 55, in the example shown having a nut 56 on its shank as shown in Fig. 4, and the plate 36 may also be provided with a countersink hole 57 for the reception of a head 58 of a screw 59, in the example shown, having a nut 60 on its shank, placed and tightened in the relationship shown in Fig. 4 after adjustment of the plate and tightening of the screw 55, to bring about desired relationship between the casket top mold and panel, after trimming.

It is preferred to also provide means to normally bias the lever 24 in juxtaposed relation to the panel top. This means may comprise a leaf spring 62, having its one end portion secured, as by rivet 63, upon an end portion of plate 35 and extending over a notched portion 64 open to the margin of the plate between ears 37, the free end of the spring engaging beneath an inwardly notched portion 65 of a skirt of minor or reduced portion of 32 of lever 24.

The cavity 34 may also accommodate a lock mechanism 67 the bolt 68 of which cooperates with a keeper 69 carried by plate 35. A typical lock mechanism is shown in Fig. 8, comprising a casing 70, which may be riveted or otherwise secured to the lever 24, in which the bolt 68 is reciprocated by the ward of a key 71, the bolt being so shaped as to cooperate with a detent portion 72 of the lock frame to hold the bolt in a locked or unlocked position, a traveling leaf spring 73 being carried by the bolt and bearing against an abutment 74 in such manner as to yieldably bias the bolt toward the detent portion 72.

The keeper 67 may be formed by cutting the body portion 36 in U-shape to provide a tongue 75 which may be upstruck and bent in L-shape to provide a flange 76 beneath which the bolt 68 engages when the lever 24 is in normal position, and the bolt is thrown to locking position by key 71.

The lock mechanism 67 also includes a key barrel 77 revolvably carried by the casing 70 and extending through a circular opening 80 in the major portion 31 of lever 24, as shown in Figs. 3 and 4.

It is believed the operation of the adjustable closing devices for burial caskets will be clear from the foregoing description. I am well aware that devices have been provided for holding the lids of trunks, suit cases, tool boxes and the like in closed position with respect to the main body portions, by the so-called overcentering or toggle action, but in these, no attempt has been made to render the mechanism such that, a very inconspicuous element remains in the normal line of vision when the receptacle is viewed from the front and the lid is open nor to provide other desirable characteristics particularly well adapted for use on burial caskets. With respect to the present invention, it will be noted from an inspection of Fig. 1 that, when the casket top panel is up, the lever 24 and link 26 are out of sight to those viewing the casket from the front, and by an inspection of Fig. 5 it will be noted that the link 26 is disposed in a very accessible position since the arms 43 thereof engage the shoulders 33 of the lever 24 which latter is held in juxtaposed relation to the panel top by the spring 62 as shown in Fig. 4. If desired, the top panel may be moved forward by the attendant grasping the link 26 in one hand, pulling it forward and easing the panel to an approximate closed position by use of the other hand easing it gently to such position, after which the link can be swung in

proper relationship to the dog 20 and final and secure latching accomplished by use of lever 24.

If the device is equipped with a lock, that may be used to ceremoniously complete the memory picture created by the funeral service. As the casket is closed for the last time it may be locked and the key presented to the family of the deceased as a memento. The lock can also be used to insure loved ones complete privacy of the contents of the casket should it be shipped to another point or should it be necessary to leave the casket at some place where no immediate member of the family could be present.

I claim:

1. An adjustable closing device adapted to be mounted on the body shell and hinged top closure panel of a casket for pulling the panel in aligning relation to the shell, comprising a dog adapted to be secured to the casket shell at its portion opposite that to which the panel is hinged, said dog comprising a shank adapted to penetrate the casket shell and securing the dog thereto, and a head at the end of said shank adapted to be spaced from the casket shell; a hinge plate; a lever pivotally carried by said hinge plate to normally lie in a first position in juxtaposed relation thereto, and to swing to a second position extending outwardly from said hinge plate, said hinge plate adapted to be secured to the casket panel at the top marginal portion thereof opposite that to which the panel is hinged and with the pivotal axis of the lever parallel to the hinged axis of the casket panel; and a link of U-shape, comprising a pair of arms with means pivotally supporting the same at adjacent end portions on said lever in an over center position when the latter is in said first position, and a bight portion joining the other ends of said arms, said bight portion being provided with a V-shaped pocket opening into said bight portion with the outermost edge of the lowermost wall of said pocket spaced inwardly of the outermost edge of the uppermost wall thereof, forming a rearwardly and downwardly opening V-shaped pocket, the uppermost wall of said pocket overlying said dog when said lever is in said first position, concealing said head of the dog, and acting as a guide for said head of the dog as said lever is moved into said first position, the apex portion of said pocket engaging the said head of the dog and tensioning said link and the pivotal connection of said link with said lever when the latter is in said first position.

2. An adjustable closing device as specified in claim 1 in which said head is tapered at its back toward said shank and the opposite walls of said V-shaped pocket are incut to have anchoring relation with said tapered head.

3. An adjustable closing device adapted to be mounted on the body shell and hinged top closure panel of a casket for pulling the panel in aligning relation to the shell, comprising a dog adapted to be secured to the casket shell at its portion opposite that to which the panel is hinged, said dog comprising a shank adapted to penetrate the casket shell and securing the dog thereto, and a head at the end of said shank adapted to be spaced from the casket shell; a link of U-shape comprising a pair of arms and a bight portion provided with a V-shaped pocket opening into said bight portion with the outermost edge of the lowermost wall of said pocket spaced inwardly of the outermost edge of the uppermost wall thereof, forming a rearwardly and downwardly opening V-shaped pocket, the uppermost wall of said pocket overlying said dog when said link is in engagement with said dog, concealing said head of the dog, and acting as a guide for said head of the dog as said link is moved into dog engaging relationship with the apex portion of said pocket engaging the said head of the dog; and means adapted to be secured to the casket panel at the top marginal portion thereof opposite that to which the panel is hinged, operatively connected to said arms of the link, opposite said bight portion thereof, for tensioning said link between said means and the engaging apex portion of said pocket and said head of the dog.

4. An adjustable closing device as specified in claim 3 in which said head is tapered at its back toward said shank and the opposite walls of said V-shaped pocket are incut to have anchoring relation with said tapered head.
